LIQUID TREATING APPARATUS

Victor A. Rohlin, Philadelphia, Pa., assignor to
Cochrane Corporation, Philadelphia, Pa., a corporation of Pennsylvania

Application May 24, 1932, Serial No. 613,213

10 Claims. (CL. 261—23)

The present invention comprises improvements in liquid treating apparatus and particularly in steam and water contact apparatus such as that used in heating and degasifying liquids. One general object of the invention is to provide improved fluid spray apparatus and another and more specific general object of the invention is the provision of improved means for bringing the liquid into contact with the vapor of the liquid which thereby liberates gases previously held in solution in the liquid. The invention in the form illustrated was primarily devised and is especially adapted for use in heating and deaerating water to be used as boiler feed water or for other purposes for which hot water practically free from oxygen is required or desirable.

In water heating and deaerating apparatus heretofore developed and in use it is and has been customary to pass the water in film like and broken streams over a superimposed set of trays located in a space into which steam for heating and deaerating water is admitted. Under the more usual conditions of operation trays, used as described, form practically effective and desirable means for effecting the desired steam and water contact. In some cases, however, as in marine service the use of trays is objectionable because of the weight and the bulk of the apparatus necessarily resulting from their use. In some cases also the efficiency of the ordinary tray means for effecting steam and water contact is impaired by imperfect distribution of water on the trays, such as may result from the movement of a ship in which the heating and deaerating apparatus is employed, and such as may result from substantial deposits on the tray of impurities contained in the water treated, when the latter contains considerable amounts of impurities precipitated from the water and collecting on the trays.

In a copending application for patent, Serial No. 556,738, filed August 13, 1931 jointly by George H. Gibson and myself water heating and deaerating apparatus is disclosed in which the more usual tray arrangements are dispensed with and the desired liquid and vapor contact action is secured by discharging the water in a multiplicity of jets into a steam space into a lower portion of which the steam used in heating and deaerating the water is discharged into a jet subjecting the water to an atomizing action made effective by baffle means interposed between the water and steam jet levels and diverting the falling water into suitable proximity to the steam jet or jets.

The present invention comprises improvements on apparatus of the type disclosed in said copending application devised with the primary objects of insuring a desirable uniformity of water jet discharge even under such adverse conditions as may be experienced on a ship in heavy weather, and with the object of simplifying and improving the water collecting means employed to pass the falling water into proper contact with the atomizing steam jet or jets and which also serve to guide the steam flow in the apparatus.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Of the drawings:

Fig. 1 is an elevation mainly in section, and

Fig. 2 is a plan view with parts broken away and in section.

In the drawings I have illustrated the use of my improvements in a water heating and deaerating device A especially devised and adapted for marine use, but not necessarily limited to such use. As shown the device A comprises a casing or housing having a main lower body portion of rectangular outline and an upper or dome portion A' curving circularly about the central vertical axis of the device, but it is to be understood that the general form of the casing is not an essential feature of the invention. As will become apparent, however, it is desirable that the upper portion of the steam space within the casing, and particularly that the portion of said space within the dome portion A' should be symmetrical about a vertical axis. As shown the casing portion A' is formed with a central top opening A² surrounded by an uprising flange A³, which forms a seat for the circumferential flange portion B' of a structure B, the flange B' being secured against the flange A³ by bolts C.

In the preferred construction illustrated, the structure B is formed with a water inlet passage D comprising a horizontal portion connected at its inner end to the upper end of a depending portion. The outer end of the passage D is surrounded by a flange B² for connection to a water supply pipe which is not shown. The depending

portion of the passage D is surrounded by a depending tubular portion B³ of the structure which extends axially downward through the opening A² but does not fill the latter. The 5 tubular portion B³ of the structure B is spaced away from the outer wall of that structure to provide a space E' opening at its lower end to the interior of the casing part A' and leading to an outlet E surrounded by a flange B⁴.

10 The space E' and the outlet E forms an outlet vent passage for air liberated in the device A. An external vent condenser (not shown) such as is usually employed in water heating and deaerating apparatus when conditions make it 15 desirable to condense steam from the air steam mixture leaving the deaerating apparatus, may be connected to the flange B⁴.

The tubular portion B³ is provided at its lower end with a flange B⁵ from which is suspended 20 a water distributing head or casing F. The latter is formed with a multiplicity of valved outlet ports F'. As shown there are eight such outlet ports distributed symmetrically about the axis of the head F and structure B. As shown, 25 a valve seat member F² is mounted in each outlet opening F'. Each valve seat member F² is formed with a spider portion, forming a guide for the stem f' of a corresponding valve f. Each valve seat member F² is also formed with a con- 30ical valve seat, and each valve f is formed with a conical valve seat engaging surface. In consequence the discharge past each valve f when the latter is not fully closed is in the form of a conical sheet of water. With a substantially 35 constant water supply pressure in the passage D, the thickness of the conical sheet of water discharged and the volume of discharge through each outlet F', will vary through wide limits in accordance with the extent to which the cor- 40 responding valve f is opened. Advantageously and as shown, the axis of the conical discharge through each outlet lies in a plane radial to the axis of the vertical portion of the passage D, and is upwardly inclined, so that the water dis- 45 charged impinges against the top wall of the dome A' and against the hereinafter mentioned vertical cylindrical flange or baffle K.

In accordance with the present invention the various valves f are caused to have similar open- 50 ing and closing movements and similar positions relative to their respective valve seats at all times, so that the volumes and velocities of discharge through the different outlet ports are approximately equal at all times, even though 55 the device A is mounted in a ship and the latter is pitching and rolling.

The means shown for causing the different valves f to have similar movements toward and away from their seats comprise an individual 60 operating lever G for, and having one arm connected to the stem f' of each valve f. Each lever G is pivotally mounted on a spider or support in the spray head casing F and has a second arm extending radially inward toward the axis of 65 the head. The inner ends of the levers G are rounded and are received between spaced apart flange portions G² carried by an axially disposed and axially movable plunger G'. The latter has a bearing for its upper portion in a 70 spider member F³ and has a bearing for its lower end in a socket portion F⁴ of the head F. The plunger G' is connected by a link G³ to an arm H' carried by a horizontal rock shaft H journalled in the side walls of the upper hori- 75 zontal portion of the passage D.

An externally projecting end of the shaft H carries a crank arm H² connected to a valve loading mechanism which is shown as comprising a link H³ connected at one end to the free end of the arm H² and having a spring follower or abutment nut H⁴ threaded on its other end. A helical spring H⁵ surrounds the link H³ and extends between the abutment nut H⁴ and an abutment bracket B⁶ carried by the structure B. The pressure of the water acting 80 on the inner sides of the valves f and tending to move those valves away from their seats is opposed by the tension of the spring H⁵. That tension may be adjusted by turning the nut H⁴ in one direction or the other about the threaded portion of the link H³. 85

The water discharged from the spray head ultimately strikes upon a conical baffle I provided with a central discharge opening I' at its lower end and terminating at its upper edge in a cylindrical flange I² smaller in diameter than the dome portion A' of the casing and spaced away from the latter. As shown the baffle I is formed of metal plate and is supported by plate like ribs J welded at their inner 90 edges to the outer side of the cylindrical portion I² of the baffle I and welded at their outer edges to the side wall of the dome A'. The roof of the latter is provided with a depending cylindrical baffle K of smaller diameter than the cylindrical portion I² of the baffle I. The lower edge of the baffle K is spaced away from the baffle I, but is located at a level below that of the upper edge of the baffle portion I². The baffle K prevents the water discharge through 100 the orifices F' from entering the space between the baffle portion I² and the surrounding wall of the dome A', but does not interfere with the hereinafter described flow of steam upward along the underside of the conical portion of the baffle I and over the upper edge of the baffle portion I² into the space traversed by the jets of water discharged through the orifices I'. 105

To prevent undesirable movement of the water over the baffle I in a circumferential direction 110 and to prevent the accumulation of an undue amount of water on one portion of the baffle, baffles L are radially disposed in the space above the baffle I. These baffles advantageously fit 115 against and are welded to the upper side of the conical portion of the baffle I and to the inner side of the baffle portion I², and extend upward into proximity with the dome A' to which they may or may not be connected in a suitable manner, as by spot welding. Advantageously and 120 as shown each baffle L comprises a portion L³ extending upward at the outer side of the baffle K to the level of the upper edge of the baffle portion I². To avoid expansion difficulties and 125 facilitate assemblage the baffles L are advantageously shaped to provide clearance between their adjacent edges and the baffle K. At its inner edge each baffle L is advantageously provided 130 with a transverse portion L² forming ribs extending laterally away from the baffle at each side of the latter. Each portion L² may be a bent bar of metal welded to the inner edge of the body portion of the corresponding baffle L. Each adjacent pair of baffles L form the side walls of 135 a water heating and deaerating chamber or compartment which receives the total discharge through a corresponding orifice F'. The inner edges of the baffles L are undercut so that the corresponding rib portions L² tend to deflect 140 water running down the sides of the baffles 145 150

outwardly into proximity with the margin of the central bottom opening I' in the baffle I , so that all of the water is brought into proper relation with the steam atomizing means now 5 to be described.

Steam is supplied to the device A through external piping, not shown, connected to the flanged outer end of a tubular steam conduit M extending through the side wall of the body portion 10 of the casing of the device A adjacent the top of said side wall. The conduit M is connected at its end to, and discharges steam into an atomizing valve casing N which as shown has a circular discharge opening at its upper side 15 symmetrically disposed with respect to the vertical axis of the apparatus. This discharge opening is surrounded by a valve seat member n mounted on the valve body N . The valve seat member n is formed at its upper side with a 20 valve seat n' in the form of a conical annulus surrounding the axis of the apparatus. Advantageously and as shown the conical angle of the seat n' is slightly more acute than the angle of the conical portion of the baffle I . The valve 25 seat n' is at the inner side of and slightly above the inner edge of the upper side of a conical flange portion n^2 of the valve seat member n . The diameter of the outer edge of the seat n' is appreciably smaller, but the diameter of the 30 upper and outer edge portion of the flange n^2 is somewhat greater, than the diameter of the central opening I' of the baffle I . In consequence the flange n^2 forms the outer wall of a 35 sort of annular trough in position to receive the water running down the upper side of the baffle and passing downward through the opening I' .

Associated with the valve seat n' is a valve member N' of inverted cup shape having a conical seat engaging surface N^2 adapted to engage the seat n' . The valve member N' is carried by a depending valve stem N^3 extending downward through an opening in the bottom wall of the casing, a stuffing box n^3 being provided to 45 prevent leakage of steam downward along the stem N^3 . The upper portion of the stem N^3 has a guide bearing N^4 carried by a spider portion n^4 of the valve seat member.

The valve N' is loaded or biased towards its 50 closed position by means of a rock shaft O journaled in the casing of the device A and provided within the latter with a crank arm O' connected by a link O^2 to the lower end of the valve stem N^3 . Externally of the casing of 55 the device A the shaft O carries a lever O^3 to one arm of which a spring abutment member O^4 is pivotally connected. The abutment O^4 engages the lower end of a helical spring P which is compressed between that abutment and 60 an upper abutment Q having a stem Q' threaded through a bracket A^4 carried by the outer wall of the housing body of the device A . The tension of the spring P and thereby the loading force on the valve N' , may be varied by rotating the stem Q' in its threaded bracket support. The second arm of the lever O^3 carries 65 an adjustable counterweight R which approximately balances the weight of the valve N' so that the action of the loading spring P is not 70 significantly modified by the weight of the valve, or, in marine service, by any tendency of the valve to move toward and away from its seat as a result of ship movements. In this connection it is noted that the plunger G' and associated parts may readily be proportional to sub-

stantially counterbalance the water distribution valves f .

In the normal intended operation of the apparatus described, the loading force acting on the steam supply valve N' is so adjusted relative to the conditions of operation as to insure an adequate and approximately constant linear velocity of steam jet discharge under all loads. The conical sheet of steam discharged between the seat n^2 and the valve seat engaging portion N^2 of the valve member N' impinges against the water passing downward through the opening I' and subjects the latter to an atomizing action. In large part the water is subjected to said atomizing action and is swept outward into the space surrounding the flange n^2 without coming into contact with the latter. Any water collecting on the flange n^2 is subjected to an atomizing action and swept off the flange by the steam jet. The bulk of the water passing downward through the opening I' will pass downwardly through the portion of that opening adjacent its margin, in part because of the deflecting action of the ribs L^2 , the lower ends of which surround and are spaced away 100 from the upper portion of the valve N' . Any water falling on the top of the valve N' and running down the cylindrical side of the latter, eventually passes directly into the path of the steam discharged through the space between 105 the valve seat n' and the valve seat engaging portion N^2 of the valve.

The steam sweeps upward along and in contact with the underside of the baffle I and thence passes around the upper edge of the baffle portion I^2 and is deflected downwardly against the upper side of the conical side of the baffle by the baffle K and thence passes out into the chambers or compartments separated by the baffles L and traversed by the water jets discharged through the different orifices F' . The passage of the steam along the baffle I gives the latter a highly efficient tray heating and deaerating action, both because of the movement of the steam along the water films or 120 streams on the upper side of the baffle I and by heating the underside of the baffle.

As will be apparent from what has been previously said, the spray head device F with its valves f supplies the proper proportion of the 125 total amount of water treated to each of the different chambers or compartments between the different pairs of baffles L , and insures a jet velocity of discharge under all loads adequate for the proper distribution of the water introduced into the different chambers or compartments. If the apparatus is operated, as will normally be the case, with a water supply pressure automatically increasing as required to force the water into the heating and deaerating 130 apparatus as rapidly as it becomes available, the loading and control means acting on the different valves f will insure the proper jet velocity of discharge through each orifice F' at light loads as well as at heavy loads. With normal or usual 135 steam and water supply pressure and temperature conditions, the amount of steam required for a given heating and deaerating effect necessarily varies in approximate accordance with the amount of water supplied. Under such conditions when the water supply to the device A increases, the increased steam condensing capacity of the water tends to create a drop in steam pressure in the device A . This by reducing the back pressure on the valve N' causes the latter 140 145

to open more widely and thereby tends to correspondingly increase the rate of steam supply to the heater. Conversely when the water supply diminishes, the pressure in the device A tends to rise thereby increasing the back pressure on the valve N' and causing a partial closing movement of the latter. In consequence the valve N' thus tends to open and close as required to maintain an approximately constant pressure in the steam space in the device A and a rate of steam supply approximately proportional to the rate of water supply.

A special advantage of the construction described is that the structure B is a unitary mechanical structure which can be assembled and adjusted prior to its mounting in the device A and can be removed from the latter when necessary for inspection, cleaning, repairs or adjustment both of the component parts of the structure B and of the apparatus within the upper portion of the device A.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. In water and steam contact apparatus, the combination with a housing enclosing a steam space comprising a central portion and a series of compartments surrounding said space, of a water spray head located in said central portion and having a separate jet outlet opening for and delivering water into each of said compartments, and means for supplying steam to said space.

2. In water and steam contact apparatus, the combination with a housing enclosing a steam space comprising a central portion and a series of compartments surrounding said central portion, of a water spray head located in said central portion and having a separate jet outlet opening for and delivering water into each of said compartments, valves controlling the different outlets and tending to open under the pressure of the liquid in said spray head and controlling means connecting said valves compelling proportional movements of the valves toward and away from their seats and means for supplying steam to said space.

3. In water and steam contact apparatus, the combination with a housing enclosing a steam space comprising a central portion and a series of compartments surrounding said central portion, of a water spray head located in said central portion and having a separate jet outlet opening for and delivering water into each of said compartments, valves controlling the different outlets and tending to open under the pressure of the liquid in said spray head, controlling means connected to said valves compelling proportional movements of the valves toward and away from their seats and including means subjecting the valves to a yielding loading force opposing the tendency of the valves to open under said pressure, and means supplying steam to said space.

4. A unitary water spray structure having a water inlet, and a multiplicity of spray outlets and a separate movable valve member for each of said outlets regulating the jet discharge through the latter and having a tendency to open under the pressure of the water sprayed, linkage means mounted in said structure and compelling the different valve members to have definitely proportional opening and closing movements and means acting on the first mentioned means to subject said valve members to a yielding loading force opposing the said tendency of the valves to open.

5. A unitary water spray structure having a water inlet and a multiplicity of spray outlets, a separate movable valve member for each outlet regulating the jet discharge through the latter and having a tendency to open under the pressure of the water sprayed, and means for causing said valve members to have definitely proportional opening and closing movements and for subjecting the latter to loading forces opposing the said tendency comprising a rock shaft mounted in said unit, loading means tending to rotate the rock shaft in one direction, and operating connections between said shaft and the different valves through which the movements of each valve is positively related to the movements of each other valve and to the movements of said rock shaft.

6. In water and steam contact apparatus, the combination with a housing enclosing a steam space comprising a central portion and a plurality of compartments surrounding said space and having bottom walls inclined to pass water to said central space, of water spray means located in said central space and discharging water jets into the different compartments, and means for subjecting the water passing downward from said bottom walls to the action of said steam and for causing the latter to pass upwardly along the undersides of said bottom walls and into said compartments at the outer edges of the latter.

7. In steam and water contact, the combination with a casing of a partition within said casing formed with a central aperture and upwardly inclined from said aperture, partitions dividing the space above said partitions into a series of compartments surrounding a central portion above said aperture, water spray means in said central space portion discharging water into the different compartments and steam spray means located below said aperture and discharging steam outwardly past the margin of said aperture along the underside of said partitions, said compartments communicating with and receiving steam from the space beneath said partition adjacent the periphery of the latter.

8. A unitary water spray structure comprising a tubular body with a head portion at one end of said body, said head portion being formed with a water inlet opening into said body and with an air outlet opening with a portion surrounding said body but separated therefrom by a space from which said outlet opens and with a flange carried by said portion and adapted to seat at the margin of an aperture in the wall of a water heating and deaerating space with said body extending through but not filling said aperture, said body being provided at its other end with a multiplicity of water spray outlets, valves controlling said outlets and valve controlling means including adjustable valve
